UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

BOWLING-ALLEY BALL RETURN.

Application filed September 4, 1925. Serial No. 54,428.

To all whom it may concern:

Be it known that I, JOSEPH W. BISHOP, a citizen of the United States, residing at Muskegon, in the county of Muskegon and 5 State of Michigan, have invented certain new and useful Improvements in Bowling-Alley Ball Returns, of which the following is a specification.

This invention relates to a novel and improved 10 bowling alley ball return and more particularly to a construction which forms an improvement over that disclosed and claimed in my co-pending application Serial No. 740,539, filed September 29, 1924.

15 A bowling alley ball return commonly is connected with a receiving track which may be elevated to a proper height for the ready taking of balls therefrom without the player having to stoop. In my aforesaid co-pending 20 application I described and claimed a means for guiding and deflecting the ball to the elevated receiving track and for retarding its movement so that when it reaches the receiving track its speed is such 25 that there is no danger of injury either to the balls themselves or to the fingers of a player, who may be taking a ball from the receiving track.

30 Bowling is done with different sizes of balls depending upon the character of game which is being played and consequently a device which would be adapted to operate upon a ball of one size in the desired manner, would not function with a ball of another 35 size. Therefore, it is the principal object of my invention to provide a combined deflector and retarder so mounted as to function in the desired manner and to be capable of adjustment so that it may be 40 used with any size of ball.

A further object of my invention is to provide novel and improved means for securing in place the strap which forms the combined deflector and retarder, or as it is 45 commonly known, the buffer.

In the accompanying drawings in which I have shown a selected embodiment of my invention;

50 Fig. 1 is an elevation of a portion of a ball return showing my invention in place thereon.

Fig. 2 is a view similar to Fig. 1, but showing the device adjusted for use with a different size of ball.

Fig. 3 is a detail of the strap forming the 55 buffer.

Fig. 4 is a longitudinal sectional view on an enlarged scale showing the details of the base which adjustably supports the buffer.

Fig. 5 is an end elevation of the invention, being taken from the right of Fig. 4.

Fig. 6 is a section on the line 6—6 of Fig. 4.

Referring now to the drawings in detail the numeral 1 designates a return track 65 which leads from the pit end of the alley to the player's end. Longitudinally spaced from the end of the track 1 is an elevated receiving track 2 and connecting the adjacent ends of these two tracks is an upwardly 70 curved track 3, it being noted that this track is curved upwardly throughout its entire length from the receiving track to the return track. At the point of connection between the tracks 2 and 3 there is provided 75 an elevated juncture 4 whereby when a ball passes this point it will receive sufficient momentum to roll along the track 2. Disposed opposite the juncture 4 is a buffer comprising a strap 5 placed at a proper angle to 80 deflect a ball from the upwardly curved connecting track 3 to the receiving track 2 in the manner fully set forth in my aforesaid co-pending application.

Disposed beneath the lower end of the 85 track 3 is a base 6. This base comprises a plate 7 having ears 8 for the reception of bolts or other fastening means by which the base may be secured to the floor. In the 90 sides of the plate 7 are provided guides in the form of grooves 9 within which are received the feet 10 of the standards 11 forming a support for the buffer to be described presently. These standards are bellied out, 95 as shown at 12 to permit the passage therebetween of the largest size bowling ball and when the parts are in the position shown in Fig. 1, it will be seen that the lower curved surfaces 13 of these bellied out portions form a practical continuation of the rails 100 forming the connecting track 3.

The plate 7 is provided with an upstanding centrally disposed spacer 14 between which and the standards 11 are received the rails 15 of the track 3. Above the grooves 9 105 the plate 7 is formed with shoulders to receive corresponding shoulders 16 upon the standards and thus provide additional guid-

ing and steadyng means as will be evident to those skilled in the art. The spacer 14 is braced at one end by means of the web 17 and is flattened out at its bottom portion, 5 as shown at 18 to form a portion of the base extending between the standards 11, as plainly shown in Fig. 6. This portion 18 of the base is slotted, as shown at 19, to receive a bolt 20 extending through both 10 standards and the base. By this means the standards may be adjusted to any desired position and secured in that position by tightening of the bolt.

Disposed between the upper portions of 15 the standards are a pair of rolls 21 and 22. Trained over these rolls is a buffer formed of the strap 5 and this strap is preferably folded on itself at its ends to form loops, the ends being secured by rivets or other 20 fastening means 23. Received within the loops are transverse pins 24 and the material of the strap is cut away at 25 to form slots. This arrangement provides a very 25 convenient structure for the securing of the strap in position. As plainly shown in Figs 1 and 2, the strap is trained over the two rolls 21 and 22 and the ends thereof are joined by means of a turnbuckle 26 provided at its ends with hooks 27 which are 30 inserted in the slots 25 and then the turnbuckle may be tightened until the strap receives its desired tension. Thus I provide an extremely simple and efficient structure 35 whereby a strap may be readily replaced without any complicated operations, such as would be necessary if the turnbuckle were permanently secured to the strap.

From the above it will be apparent that I 40 have provided a novel and improved device which may be employed with any size of bowling ball. All that is necessary when the alley is to be used for bowling with a different size of ball than what is being used, 45 is to loosen the bolt 20 and adjust the standards by sliding them bodily along the base. Usually two standard sized balls are used and I therefore make the slot 19 of a proper length so that when the bolt is engaged with 50 either end thereof the buffer is in proper position for either the larger or the smaller size ball. This eliminates any guess work as to the proper position at which the device is to be placed, but on the other hand, it 55 permits of an adjustment, if such is found necessary.

I am aware that changes in the form, construction and arrangement of parts may be made without departing from the spirit and 60 without sacrificing the advantages of the invention and I reserve the right to make all such changes as fairly fall within the scope of the following claims.

I claim:

65 1. A bowling alley ball return comprising a return track, an elevated receiving

track in alignment therewith, an upwardly curved track connecting the adjacent ends of said return and receiving tracks, a buffer forming a combined deflector and retarder adjacent the juncture of said receiving track 70 and said connecting track, and means for adjusting said buffer longitudinally of said tracks.

2. A bowlling alley ball return comprising 75 a return track, an elevated receiving track in alignment therewith, an upwardly curved track connecting said return track and receiving track, a base, a support slidably mounted on said base, and a buffer carried by said support and disposed adjacent the juncture of said connecting track with said receiving track.

3. A bowling alley ball return comprising 80 a return track, an elevated receiving track in alignment therewith, an upwardly curved track connecting the adjacent ends of said return track and said receiving track, a base adjacent the lower end of said connecting track and provided with guides, a support having feet co-operating with said guides and slidale in respect thereto longitudinally of said tracks, means for securing said support in position, and a buffer carried by said support adjacent the juncture of said connecting track and said receiving track.

4. A bowling alley ball return comprising 85 a return track, an elevated receiving track in alignment therewith, an upwardly curved track connecting the adjacent ends of said return track and said receiving track, a base disposed adjacent the lower end of said connecting track, a support on said base, co-acting guide means on said base and said support permitting movement of said support longitudinally of said tracks, a slot extending through said base, and a bolt received in said slot and carried by said support, and a buffer carried by said support adjacent the juncture of said connecting track and said receiving track.

5. A bowling alley ball return comprising 90 a return track, an elevated receiving track in alignment therewith, an upwardly curved track connecting the adjacent ends of said return track and said receiving track, a base disposed beneath the lower end of said connecting track, grooves in either side of said base, a support comprising standards disposed on either side of said base, and having feet received in said grooves, a bolt passing through said standard and through said base, and being received within a slot in said base, and a buffer supported between said standards and adjacent the juncture of said receiving track and said connecting track.

6. A bowling alley ball return comprising 95 a return track, an elevated receiving track in alignment therewith, an upwardly curved track connecting the adjacent ends of said

- return track and said receiving track, a base disposed beneath the lower end of said connecting track, grooves in either side of said base, a support comprising standards disposed on either side of said base, and having feet received in said grooves, a bolt passing through said standard and through said base, and being received within a slot in said base, a spacer on said base between which and said standards the rails of said connecting track are received, and a buffer supported between said standards and adjacent the juncture of said receiving track and said connecting track.
7. A bowling alley ball return comprising a support formed of spaced standards, a pair of rolls, a strap trained over said rolls and terminating at each end in a loop, a transverse pin disposed in each loop, the material of said strap being cut away to form a slot at each pin, and a turnbuckle having hooks inserted in said slots to engage said pins and fasten said strap in place on said rolls.
8. A bowling alley ball return comprising a support, a pair of rolls thereon, a strap trained over said rolls and terminating at each end in a loop, a transverse pin disposed in each loop, the material of said strap being cut away to form a slot at each pin, and means for connecting the ends of said strap and provided with hooks engaging said pins at said slots.
9. A bowling alley ball return comprising a return track, an elevated receiving track in alignment therewith, an upwardly curved track connecting said return track and receiving track, a base, a support on said base, a buffer carried by said support and disposed adjacent the juncture of said connecting track with said receiving track, and means for adjusting said support on said base to vary the relation of said buffer to said juncture.
10. A bowling alley ball return comprising a return track, an elevated receiving track adapted to receive balls from said return track, a buffer adapted to control the movement of balls passing from said return track to said receiving track, and means to adjust said buffer to permit its use with various sizes of balls.

JOSEPH W. BISHOP.
